PROCESS OF CRYSTALLIZING SUGAR.

(Application filed Feb. 15, 1901.)

(No Model.)

UNITED STATES PATENT OFFICE.

HERMANN CLAASSEN, OF DORMAGEN, GERMANY.

PROCESS OF CRYSTALLIZING SUGAR.

SPECIFICATION forming part of Letters Patent No. 690,014, dated December 31, 1901.

Application filed February 15, 1901. Serial No. 47,511. (No specimens.)

To all whom it may concern:

Be it known that I, HERMANN CLAASSEN, a subject of the King of Prussia, German Emperor, and a resident of Dormagen, Rhenish 5 Prussia, German Empire, have invented new and useful Improvements in Processes of Crystallizing Sugar, of which the following is a specification.

This invention has for its object to provide 10 a process for regulating the supersaturation of the molasses of a masse-cuite produced from impure saccharine solutions, which molasses surrounds the crystals while crystallization in motion is carried on, such regulation being 15 effected by a predetermined addition of water in such a manner that according to the temperature and the purity of such sugar solution the most favorable conditions are kept up for causing the crystallization of the sugar 20 and its depositing on the existing crystals and for preventing the formation of small new crystals as far as such prevention is practically required. The degree of said supersaturation will be different from—that is, lower 25 than—that prevailing in the boiling of the original solutions. In the latter case a proportionately higher supersaturation may prevail, because with the boiling in the vacuum-pan the crystallization or deposition upon the 30 existing crystals will take place much more rapidly than with the cooling-down crystallization and because the viscosity which prevents crystallization will not assert itself at high temperature, and, finally, because the 35 motion of the mass is a very thorough one, in consequence of which the temperature will be uniform throughout the entire mass. In the case mentioned the sugar which separates in great quantities at the high supersaturation 40 of the solution will only enlarge the existing crystals and will form no new grain or crystals. Now, according to the process of this invention, the addition of water during crystallization of the masse-cuite in the crystallizing apparatus is regulated in such manner that at every stage of the crystallizing of 45 said masse-cuite a predetermined degree of supersaturation of the molasses in which the

crystals are contained is kept up, said masse-cuite being continuously or periodically agitated and cooled down. Cooling down of the mass in the crystallizer should, however, take place slowly. To stir the mass rapidly by mechanical means in order to cause a thorough mixing will not do, because in this case, especially with very impure molasses, the mass will become foamy. A partial greater cooling may take place in the mass at the walls of the crystallizer, such parts of the mass thereby becoming supersaturated to a higher degree 50 than the warmer parts of the mass. This will particularly take place at the beginning of the crystallizing process in the crystallizer when the masse-cuite is still hot. By the cooling down the supersaturation of the molasses will 55 materially be increased, because by the influence of the non-sugar substances and by the viscosity of the mass, which will increase during the cooling, the power in the masse-cuite to prevent crystallization will become so great 60 that the entire mass of sugar which with the decreasing temperature is contained in the saccharine solution in an amount exceeding 65 that corresponding to such temperature (supersaturation) will not find time and opportunity to deposit upon the existing crystals. Thus under all these circumstances in the masse-cuite the formation of new grain will 70 easily take place, which never develops to such sizes that it might be recovered in the 75 centrifugal machine. Thus the yield of sugar is reduced as it is to a great extent expelled by centrifugal action with the final molasses, and, further, the quotient of the final molasses separated by centrifugal action is increased, 80 and centrifugal separation is interfered with by the formation of a film on the sugar in the 85 centrifugal separator. According to the present invention a predetermined degree of supersaturation of the molasses is to be kept up 90 during the entire operation of crystallizing, so as to obtain a proper crystallizing and to avoid the above-mentioned defects. The supersaturation—that is, the quotient or degree of supersaturation—has to be so selected 95 for each period of the crystallizing operation

that it does not arrive at such a height or limit as to cause formation of new crystals. It is a matter of experience that the formation of new crystals in the sugar solutions of 5 masse-cuite begins at a supersaturation quotient of above 1.25. Therefore water has to be added to the mass in the crystallizer to such an extent that the supersaturation quotient of 1.25 is not exceeded, taking in consideration the reduction of the supersaturation which takes place by the formation of a crystal deposit of sugar upon the existing crystals.

I prefer to proceed as follows: After boiling 15 in the vacuum-pan has been completed water is drawn in at this stage in order to bring the supersaturation of the sugar solution down to the desired quotient, and then the mass is allowed to run into the crystallizers, in which a further addition of water in proportion to the cooling takes place. In explanation I would state that the term "quotient of supersaturation" is defined as the 20 quotient obtained by dividing the quantity 25 of sugar dissolved in one part of water in the concentrated sugar solution by the quantity of sugar contained in one part of water at the same temperature in the saturated solution of sugar. As to the addition of water, it has 30 to be taken into consideration that the supersaturation during the cooling down of impure sugar solutions will rise in a far greater proportion than with the cooling of pure sugar solutions, since the state of saturation 35 will change in quite a different manner in the two cases. Not only the temperature, but also the quality and especially the quantity, of the non-sugar substances will be of great influence upon the state of saturation. The 40 solubility of the sugar will be much greater in impure sugar solutions than in pure ones, such solubility increasing with the quantity of non-sugar present. Again, the influence of a given quantity of non-sugar upon the 45 solubility of the sugar is the greater the more elevated the temperature is. Thus, for instance, in a saturated solution of beet-root sugar of about sixty-three purity there are 5.8 parts of sugar dissolved in one part of water 50 at 80° centigrade—that is, 1.6 times as much as in a pure saturated solution of the same temperature—whereas the same sugar solution of about sixty-three purity is saturated at 50° centigrade if it contains in every part 55 of water 3.4 parts of sugar or 1.3 times as much sugar only as is dissolved in a pure sugar solution saturated at 50° centigrade. These figures, which indicate how many times more sugar is dissolved in impure saturated solutions in one part of water than in pure ones of equal temperature, are the quotients of saturation. The following table indicates the 60 quotients of saturation for sugar solutions of about sixty-two to sixty-four purity:

There are dissolved in one part of water—

	In the saturated solution of sugar of 64 purity.	In saturated pure solution parts of sugar.	Quotient of saturation of the syrup.
At 80° centigrade	5.6	3.6	1.6
At 70° centigrade	4.8	3.2	1.5
At 60° centigrade	4.1	2.9	1.4
At 50° centigrade	3.4	2.6	1.3
At 35° centigrade	2.8	2.3	1.2
At 20° centigrade	2.3	2.0	1.15

In my new process the supersaturation by addition of water is so regulated that corresponding to the purity of the original sugar solution and to the decreasing temperature the quotient of supersaturation remains between 85 1.05 and 1.25. This treatment of the second masse-cuite must, according to the conditions of crystallization in motion, require a longer period than with the masse-cuite of the first products, because the second masse-cuite will 90 crystallize more slowly, owing to the influence of non-sugar matters. Therefore the desired purpose in view—namely, a thorough crystallization—will not be arrived at if the addition of water should take place during a rapid 95 cooling within a few hours. Such cooling should be so slow that the temperature for centrifugal separation will be obtained only after sixty hours or even later. Since the dissolving power of the impure sugar solution 100 will, as above stated, depend also upon the purity of the same and of the masse-cuite, the addition of water will differ according to the purity of said solution or masse, because the dissolving power of the sugar solution decreases with an increase of its purity, and thereby the quotient of saturation becomes a 105 different one. Such quotient being a lower one with pure solutions than with impure ones, the following points for the addition of 110 water have to be taken into consideration: first, that the proportion of water contained in the molasses surrounding the crystals will in consequence of the crystallizing of the sugar have to increase, and that in a higher degree at the beginning than later on, because the relatively pure sugar solutions, which of course are purer in the beginning than later on when sugar has been separated and deposited on the existing crystals, will crystallize more rapidly; second, that the solubility of the sugar will decrease with the falling temperature; third, that this decrease will take place in a greater proportion than with pure or relatively pure solutions, which proportion is expressed by the quotients of supersaturation, and, fourth, that with the nearly uniform sinking of the temperature a defi- 115 120 125

nite progression in the quantity of the water to be added for each masse-cuite may be established if the purity and the contents of water of the molasses are known.

- 5 It must be especially stated that the object of this process is to obtain in the crystallizing apparatus a further crystallizing of the masse-cuite which has been emptied from the vacuum-pan into the crystallizer and to cause 70 the molasses surrounding the crystals to deposit its sugar upon the existing crystals as far as possible, so that in the following separation of the solution from the crystals such solution is a final molasses. This process 15 therefore very materially differs from those processes in which the sugar solution which surrounds the crystals is converted by boiling down and by addition of final molasses in the boiling apparatus into a final molasses 20 from which no further amount of sugar can be separated by crystallization, and in which processes the so-obtained masse-cuite is quickly cooled down in cooling apparatus provided with stirrers and diluting means are 25 only added in order to have a product readily capable of being treated in a centrifugal separator.

In order to illustrate the process which forms the subject-matter of the present application, the following example is given: A molasses of seventy-five purity issuing from a first product masse-cuite is by means of boiling to grain crystallized to such a degree that at the emptying stage the molasses of the second masse-cuite possesses a purity of sixty-five to sixty-seven. This second masse-cuite is let down into the crystallizing apparatus with the molasses containing eight and a half per cent. of water at a temperature of 93° 40 centigrade. The cooling down in this example is so regulated that a temperature of 45° centigrade is reached in four days. The temperature will sink as near as possible in the following manner: At the end of the first day 45 to about 80° centigrade, at the end of the second day to about 70° centigrade, at the end of the third day to about 58° centigrade, and at the end of the fourth day to about 45° centigrade. At 88° centigrade the addition of 50 water is commenced with the following quantities: At 88° centigrade for every cubic meter of masse-cuite, 2.6 liters; at 84° centigrade for every cubic meter of masse-cuite, 2.6 liters; at 80° centigrade for every cubic meter of masse-cuite, 5.3 liters; at 76° centigrade for every cubic meter of masse-cuite, 5.3 liters; at 72° centigrade for every cubic meter of masse-cuite, 5.3 liters; at 68° centigrade for every cubic meter of masse-cuite, 5.3 liters; at 64° centigrade for every cubic meter of masse-cuite, 5.3 liters; at 60° centigrade for every cubic meter of masse-cuite, 5.3 liters; at 56° centigrade for every cubic meter of masse-cuite, 5.3 liters; at 54° centigrade 65 for every cubic meter of masse-cuite, 5.3

liters; at 50° centigrade for every cubic meter of masse-cuite, 5.3 liters; and at 45° centigrade for every cubic meter of masse-cuite, 5.3 liters. The mass will thus be at the end of the fourth day desaccharized down to 70 purity of final molasses, and the final molasses, which is practically free from fine crystals, is ready for centrifugal separation, as it is only slightly supersaturated.

It is not a matter of necessity to exactly 75 regulate the cooling down of the second masse-cuite in the manner above prescribed. It might be preferred, as soon as the temperature has sunk several degrees, to commence with the addition of the required quantity of 80 water. This addition of water may take place continually during the entire period of cooling or periodically, as in the example shown. It must take place at all events early enough to avoid exceeding the desired 85 quotient of supersaturation.

The following figures of proportion are given to illustrate how the addition of water may vary with masse-cuites of variable purity and different contents of water of the molasses 90 while running off.

Contents of water of the crystals surrounding molasses while running off.	Purity of the masse-cuite.			
	70.	75.	80.	95.
8 per cent.....	Liters. 7.5	Liters. 6	Liters. 4.3	
8.5 per cent.....	6.5	5.3	3.5	
9 per cent.....	5.5	4.5	3.0	
10 per cent.....	4.0	3.5	2.0	

100

In the accompanying drawings I have shown an apparatus suitable for carrying out my improved process:

Figure 1 is a longitudinal section of said 105 apparatus. Fig. 2 is a cross-section thereof on line *xx* of Fig. 1, and Fig. 3 is a detailed end elevation of the device for admitting the heat-regulating fluid.

The apparatus consists of a stationary drum 110 A, having heads *x* *x'* and provided with a jacket B, into which water or any other suitable heat-controlling medium may be admitted, said device comprising a pipe *a*, connected with the jacket B, and valves *b'* *b*, 115 controlling connections to pipe *a*.

D is the outlet from the jacket B.

E is an aperture through which the masse-cuite is introduced into the drum A, and *F* is an opening through which the mass may 120 be observed.

At the bottom of the drum is located an outlet *G*, provided with a valve controlled by a lever *G'*. Within the drum is arranged axially a shaft *H*, carrying a worm-wheel *J*, 125 which is rotated by a worm *K*. Stirrer-blades *I* are secured upon the shaft *H* within the drum A.

M indicates a thermometer which extends into the drum A, and *N* is a water-tank pro- 130

vided with a graduation N' and connected with the interior of the drum A by a valved pipe n . Through this pipe proper quantities of water are supplied during the cooling of 5 the mass, as hereinbefore referred to.

I claim—

The method of crystallizing sugar from a saccharine solution of a masse-cuite produced from impure saccharine solutions, which 10 consists in slowly cooling said solution while imparting motion thereto, and gradually add-

ing thereto an increasing proportion of water in such amount as to keep the quotient of supersaturation between 1.05 and 1.25.

In testimony that I claim the foregoing as 15 my invention I have signed my name, in presence of two witnesses, this 25th day of January, 1901.

HERMANN CLAASSEN.
